UNITED STATES PATENT OFFICE

JOHN LOGIE BAIRD, OF LONDON, ENGLAND, ASSIGNOR OF ONE-HALF TO TELEVISION
LIMITED, OF LONDON, ENGLAND, A BRITISH COMPANY

EXPLORING DEVICE FOR TELEVISION APPARATUS

Application filed January 6, 1928, Serial No. 244,964, and in Great Britain January 21, 1927.

This invention is for improvements in or relating to exploring devices for television apparatus, and has for its object to provide a construction of such device which will permit of the production of brighter images by the use of more than one source of light for such production, or will permit the reproduction of different portions of the same object simultaneously.

10 According to this invention an exploring device for television apparatus comprises a rotatable disc having mounted on it a plurality of sets of light-transmitting devices whereof each set is arranged in a spiral or like formation, and the devices of each set are arranged to receive and transmit light all in the same direction, which direction is different from that of the other sets.

The light-transmitting devices may be reflectors, or they may be constituted by openings in the screen or by combinations of reflectors and openings.

In one form, the invention comprises a rotatable disc having two or more spiral sets 25 of holes formed in it, and a plurality of internally-reflecting rods or tubes whereof one terminates at each hole, said rods or tubes being so disposed that their other ends all sweep along the same or substantially the 30 same path in the rotation of the disc.

In a modification of this invention, it comprises the combination with a rotatable disc formed with two or more sets of spirally-arranged holes in it, of two or more sets of 35 mirrors, each mirror mounted adjacent a hole, the mirrors of each set being disposed similarly to one another, but with the dispositions of the mirrors of the different sets different from one another.

40 Either of the above described arrangements may be modified by omitting the reflecting devices for one of the spiral sets of holes, or in yet another modification, a set of spirally-arranged mirrors may be mounted on the disc and used instead of holes therein.

In the accompanying drawing, which illustrates diagrammatically various embodiments of this invention—

50 Figure 1 is a front elevation, and

Figure 2 is a section on the line 2—2 of Figure 1, but drawn to a larger scale;

Figure 3 shows the front elevation of a modified construction;

Figure 4 is a section on the line 4—4 of 55 Figure 3, but drawn to a larger scale; and

Figure 5 is a modification showing a combination of reflecting members and apertures.

Like reference characters indicate like 60 parts throughout the drawing.

Referring first to the construction illustrated in Figures 1 and 2, the exploring device comprises a disc 10 having a spirally-arranged set of holes, the set being indicated as starting at 11 and extending completely 65 round the disc and terminating at 12. The second similar spiral set of holes commences at the hole indicated by the reference 13 and terminates at 14. As shown, the two spirals are coterminous, each exploring one half of 70 an area indicated at 15.

Each of the holes of the outer spiral 11, 12, has a small mirror 16 associated with it, and these mirrors are arranged as shown in Figure 2, at an angle of, say, 45° to the plane of 75 the disc, with the reflecting face directed radially outwards. Figure 2 also indicates the position of the mirror 17 for the last hole 12 of the spiral 11, 12.

When this construction of device is used for a television receiver, a lamp 18, whereof the brilliance is modulated in accordance with the received signals, is arranged to one side of the disc 10, as shown in Figures 1 and 2, in such a position as to project a beam of light 80 19 on to the mirrors in the spiral 16, 17. The beam 19 is of a width as shown in Figure 1 at least equal to the circumferential extent of the area 15 of the picture, and as shown in Figure 2 is of sufficient width in that plane 85 to cover all the mirrors 16 to 17, in the outer spiral. The inclination of the beam 19 and the mirrors 16, 17 is such that the mirrors reflect the beam through their corresponding holes normally to the surface of the disc 10, for example on to the screen whereon the received image is constituted and viewed.

The second or inner spiral 13, 14 is provided with a similar set of mirrors 20, 21, 90 but these mirrors are directed radially in- 100

wards (as compared with those of the outer spiral being directed radially outwards) so that they receive light from a second lamp 22.

It will be seen that with this arrangement 5 each of the lamps 18, 22 is used in conjunction with only one of the spirals of holes, and cannot produce any image by means of the spiral allocated to the other lamp.

The two spirals may be arranged in any 10 desired manner; instead of each covering half the field, each might cover the whole field, if so desired, so as to produce a picture of greater brilliancy, or each may cover a portion of the field, with the two portions 15 overlapping to produce a greater brilliancy of picture on the overlapping portions wherein the center of interest in the picture lies. Obviously, of course, any other disposition and arrangement of lamps may be used with 20 appropriate settings of the mirrors, and more than two spirals may be used, each with its own lamp, if so desired.

In the construction diagrammatically illustrated in Figures 3 and 4, the disc 23 is 25 provided with two spirals of holes, indicated at 24, 25 respectively, and with each of the holes there is associated an internally reflecting tube or rod as shown at 26. Each tube or rod is so shaped that one end of it, 27, terminates at the corresponding hole so that a beam of light within it passes out through the hole in the disc, and its other end 28 is so situated as to pass in proximity to the lamp during the rotation of the disc, and receive the beam 30 of light therefrom. As shown most clearly in Figure 4, this construction and arrangement of reflecting devices permits the two lamps to be set side-by-side whilst confining the beam from each of them to its own particular spiral of holes.

The members 26 may be of quartz or like transparent material, transmitting the light lengthwise through them by total internal reflection, or they may be of tubular construction, for example opaque, provided with an internal reflecting surface.

The members 26 for a spiral may be all of the same shape and size, as illustrated. A suitable selection of the width of the beam 50 29 (see Figure 4) may be necessitated if the free ends of the tubes or rods are not parallel with the plane of the disc, or if they are parallel therewith, the width of the beam as at 30 need be only sufficient to cover the ends 55 of the members.

Figure 5 illustrates yet another modification in which the spiral sets of light-transmitting elements on a rotatable disc 31 are 60 constituted by a spiral of holes 32 and a spiral of mirrors 33, these mirrors being set on that side of the disc which is viewed by the observer, from a point 34; in this case the spiral of holes 32 will be allotted to a lamp 35 situated behind the disc 31, and the spiral 65 of mirrors 33 will be allotted to a lamp 36

which is situated in front of the disc, the mirrors being so arranged as to reflect a beam of light from this lamp towards the observer.

Whilst various specific constructions and arrangements of devices have been described, 70 it is to be understood that the invention is not limited in this manner, for various modifications may be made. Thus, for example, various combinations of the different light-transmitting devices hereinbefore described 75 may be made with one another, as by using mirrors like those of Figure 1 for one spiral and internally-reflecting tubes or rods as in Figures 3 and 4 for another spiral, or the tubes and rods on one spiral may be used in conjunction with open holes as in Figure 5, or two sets of mirrors arranged like the mirrors 33 in Figure 5 may be used, the two sets being oppositely directed. It will be appreciated that when mirrors on the front of the 80 disc are used it is desirable that the disc itself should be of a non-reflecting preferably dull black surface.

This invention has been described in various forms for use in the receiving apparatus of a television system, but it can also be applied to the exploring device used at the transmitting station. In a preferred form for use at a transmitting station, the exploring device is used to traverse a series of images in succession over a light-sensitive cell or cells so that the cell or cells explores such images in narrow bands. By associating an image-forming device (for example a lens) with each of the light-transmitting devices in the apparatus hereinbefore described, the desired result can be obtained, the light-sensitive cells occupying positions corresponding to those of the lamps above mentioned so that each cell co-operates with a 90 single spiral of the exploring device.

When plain mirrors are used in the apparatus above described, these may be replaced by concave mirrors which will thereby serve the double purpose of transmitting the 100 light in the required direction and forming an image which is projected on the light-sensitive cell.

I claim:

1. An exploring device comprising a rotatable element, and a plurality of series of spirally arranged light transmitting means thereon, each light transmitting means including a reflecting device, the reflecting devices in each series being similarly disposed and those in different series being differently disposed.

2. In an image producing apparatus, the combination with a rotatable disc, of a plurality of groups of scanning elements carried by said disc and arranged in substantially spiral formation thereon, each element consisting of a plane mirror, and a plurality of electro-optical energy converting devices, said scanning elements being adapted to be 115 120 125 130

interposed between said devices and an image or object and serving to transmit light beams therebetween, the angular disposition of the elements being such that each group is operatively associated with a different device and with one device only.

In testimony whereof I affix my signature.
JOHN LOGIE BAIRD.
